(57) **CLAIM**

The ornamental design for a terminal box connector, as shown and described.

DESCRIPTION

FIG. 1 is a front elevation view of a terminal box connector showing our new design.

FIG. 2 is a rear elevation view thereof.

FIG. 3 is a top plan view thereof.

FIG. 4 is a bottom plan view thereof.

FIG. 5 is a right side elevation view thereof.

FIG. 6 is a left side elevation view thereof; and,

FIG. 7 is a top, front, and left side perspective view thereof. In the figures, areas or surfaces that include shade or contour lines are part of the claimed design. The dash-dot line represents the boundary of the claimed design. The broken line portion of the figures is included to show unclaimed environment only and forms no part of the claimed design.
